UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

COOKING STOVE.

Application filed December 9, 1926. Serial No. 153,496.

This invention relates generally to cook stoves and more especially to the construction of an oven or the like and a closure therefor.

It has heretofore been the common practice in oven construction, to provide a cast iron front frame for the oven, into which the oven door, also having a cast metal frame, is arranged to seat.

One object of the present invention is to 10 eliminate the cast front frame for the oven, so as to reduce the cost of manufacture.

Prior structures have also been objectionable in that the seams and joints between the usual oven section and the oven door frame 15 have a tendency to catch and accumulate dirt, and the same is true of the hinged mounting of the oven door upon the frame. It is therefore another object of this invention to provide an improved stove construction in which 20 the joints incident to the mounting of the oven door frame on the stove are substantially eliminated, and in which the hinges for pivotally supporting the door are entirely concealed when the door is closed.

25 A general object is to provide an improved stove construction in which a cheap, simple and sturdy construction coupled with a neat appearance and an easily cleaned structure are salient features.

30 Other objects and advantages will become apparent in the description and from the drawings, in which

Figure 1 is a front elevation of a stove showing the preferred form of this invention.

35 Figs. 2 and 3 are fragmentary side elevations showing the door in closed and open positions, Fig. 2 being partially broken away to show the preferred hinge construction.

Fig. 4 is a section taken on a line 4—4 of 40 Fig. 1.

For the purpose of disclosure I have chosen to portray the preferred form of the invention as embodied in a gas cook stove comprising a base or oven section 5 and a top 6 mounted on the base as by brackets 7 from each upper corner thereof, said base being supported from the floor by suitable legs 8.

The oven comprises generally a pair of side walls 9, a rear wall 10, a top 11 and a bottom 50 12 of sheet metal construction. In attaining the objects of this invention I have provided an oven door frame integral with the oven by turning the front edges of the sheet metal side walls 9 and the top 11 inwardly at substantially right angles to provide frame flanges 13

and 14. If desired the edges of the frame thus formed may be turned inwardly providing a strengthening flange 15.

A front plate 16 preferably formed of cast metal is rigidly secured across the lower portion of the base 5 to provide a false base generally designated as 17. The upper edge of the plate 16 is preferably curled inwardly and downwardly to provide a rounded upper surface (Figs. 2 and 3). A false bottom 18 is 65 secured within the oven substantially flush with the upper rounded edge of the front plate 16.

A door, having any suitable construction, such as a cast door frame 19 and a panel plate 70 20 therein, is arranged normally to rest upon the rounded upper edge of the front plate 16. The size and design of the door is such that the door, when closed, entirely conceals the oven opening and frame. A suitable handle 75 21 may be secured upon the upper edge of said door.

A pair of bent arms or levers 22 each having a recess 23 in the under side thereof are rigidly secured on the lower part of the door frame 19 near the ends thereof in such manner that when the door is in normal closed position on the stove the lever will extend inwardly and downwardly of the base. On each side of the oven both the side frame flanges 13 and the false bottom 18 are slotted, as at 24, to permit swinging movement of the levers therethrough when the door is mounted. The lower ends of these slots, it will be observed, are closed by the front plate. 90

When the door is swung open, the bottom of the door moves away from the supporting edge of the plate 16, the recesses 23 on the levers 22 bearing on the rounded edge of the plate as a fulcrum thereby supporting the 95 door. Heads 25 suitably positioned on the levers 22 are arranged to contact the frame members 13 at the horizontal or open position of the door and hold the door against further movement in that direction. These heads 100 also are adapted to interengage with the curled upper edge of the front plate in the closed position of the door, and since the slots through which the levers extend are closed at their lower ends by the front plate, it will be 105 seen that the fastening in place of the front plate serves to secure the door in operative position.

Preferably means is provided whereby the door may at all times be held securely upon 110

the stove at any position of the door. In the present instance this means comprises a resilient member such as the helical spring 26 anchored to a pin 27 or the like, secured upon the inner side of the front plate 16. A flexible member, such as a chain 28, passes around a guide pulley 29 suitably mounted beneath the false bottom at a point underlying one of the levers 22, and is connected at one end to 10 the spring 26 and at the other end to one of the hinge levers 22. Thus a counterbalance is provided acting against the weight of the door during opening and closing and exerting an effective downward pull at both positions 15 to hold the door firmly seated upon the plate 16.

It will be readily seen that a construction of a stove has been provided in which the front frame is formed of sheet metal integrally 20 with the oven, thus reducing the cost of manufacture and eliminating the joints usually incident to the interfitting door and oven frame construction.

I claim as my invention:

25 1. A stove comprising, in combination, a cooking top, a base section formed of sheet metal to provide top, bottom, side and rear walls with inturned flanges at the forward edges of the side and top walls defining a frame, brackets at the front and rear corners of the base section and secured thereto to support the top, a front plate extending across the lower portion of the base section, said plate being formed of cast metal and 30 shaped to provide a rounded upper edge, a false bottom in said base section substantially in the plane of the upper edge of said plate, and a door having a pair of supporting arms upon its inner side adapted to turn upon the 35 upper edge of said plate, said door being of a width substantially equal to the width of the oven section, and said front plate being of a thickness at its upper edge substantially equal to the thickness of the door.

40 2. A stove comprising, in combination, a cooking top, a base section formed of sheet metal to provide top, bottom, side and rear walls with inturned flanges at the forward edges of the side and top walls defining a frame, a front plate extending across the lower portion of the base section, said plate being formed of cast metal and shaped to provide a rounded upper edge, a false bottom in said base section substantially in the 45 plane of the upper edge of said plate, and a door hinged upon said front plate and arranged to overlap the sheet metal oven frame.

50 3. A stove having, in combination with an oven including two sides, a top and a bottom, said two sides and top having the edges thereof turned inwardly to provide a door frame on said compartment, a front plate secured across the lower side of said open face, a 55 false bottom within said oven, a door adapted to cover said open face and frame and to

rest on said plate, and a pair of levers on said door, said false bottom and each of said side frame members having therein openings to permit swinging movement of said levers therethrough, said door when closed being 70 supported by said plate and when open by said levers.

4. A stove comprising, in combination, an oven including an oven door frame integral therewith defining an open front face, a door for closing said face, a plate secured on the lower part of said oven and adapted normally to support said door, a pair of hinge members on said door arranged when said door is opened to pivot on said plate as a fulcrum and to support said door when open, and resilient means secured to the free end of one of said hinge members to exert a downward pull thereon, said front plate being shaped to provide a downwardly facing abutment at its upper edge and said hinge members having heads movable into engagement with said abutment as the door is moved toward its closed position.

5. A stove having an oven section with 20 sheet metal side and top walls, inturned flanges on said walls, a separately formed lower plate coacting with said flanges to form a rectangular frame, and a door having hinge members fulcrumed on said plate 25 and having heads at their inner ends adapted to engage with the front plate and the side flanges of said frame, said side flanges having slots to receive said hinge members, which slots are closed at their lower ends by said 100 front plate.

6. A stove having an oven section with sheet metal side and top walls, inturned flanges on said walls, a separately formed lower plate coacting with said flanges to 105 form a rectangular frame, and a door having hinge members fulcrumed on said plate, said side flanges having openings therein, the lower ends of which are closed by said front plate and said hinge members being entered 110 through said openings and adapted to interengage with the inner side of said frame at the edges of the openings therein, whereby to retain the door in operative relation to the frame.

7. A stove having an oven section with sheet metal side and top walls, inturned flanges on said walls, a separately formed lower plate coacting with said flanges to form a rectangular frame, and a door having hinge members fulcrumed on said plate, said side flanges having openings therein, the lower ends of which are closed by said front plate and said hinge members being entered 120 through said openings and adapted to interengage with the inner side of said frame at the edges of the openings therein, whereby to retain the door in operative relation to the frame, said front plate and hinge members further being shaped to provide a coacting 125 130

bearing surface, and spring means connected with the inner ends of the hinge members and tending to hold said coacting bearing surfaces in contact.

- 5 8. A stove having an oven section with sheet metal side and top walls with inturned flanges on the side walls, a separately formed front plate secured at its opposite ends to said side walls, and coacting with the side
10 flanges to form a door frame, a door having hinge members rigid therewith and project-

ing inwardly and downwardly from its lower edge, there being slots formed in said frame to receive said hinge members, said slots having their upper ends in said side flanges and their lower ends in said front plate, and means for holding said hinge members in operative relation to the door frame. ¹⁵

In testimony whereof, I have hereunto affixed my signature.

GEORGE E. PICKUP
